UNITED STATES PATENT OFFICE.

FRANK F. LANDIS, OF WAYNESBORO, PENNSYLVANIA.

SECONDARY ELECTRIC CLOCK.

1,313,304.

Specification of Letters Patent. Patented Aug. 19, 1919.

Application filed July 27, 1915. Serial No. 42,192.

To all whom it may concern:

Be it known that I, FRANK F. LANDIS, a citizen of the United States, residing at Waynesboro, Franklin county, and State of Pennsylvania, have invented and discovered certain new and useful Improvements in Secondary Electric Clocks, of which the following is a specification.

My invention consists of certain improvements in the details of construction and arrangement of parts of secondary clocks designed especially to form a part of an electric clock system, whereby such a clock is provided, which is simple yet positive in its 10 operation and not liable to get out of adjustment, and also one which provides a mechanism which increases the work of operating the clock in the exact proportion to the increased power of a magnet as the armature 15 approaches the magnetic field, thereby eliminating the violent shock or stroke of the armature when arrested by the magnet, all of 20 which will be hereafter more fully described in claims.

Referring to the accompanying drawings, which are made a part hereof, and on which similar reference characters indicate similar parts,

Figure 1 is a rear elevation of a secondary 30 clock movement embodying my said invention,

Fig. 2 an edge elevation of the same,
Fig. 3 a top or plan view of the same,

Fig. 4 a detail view showing the parts to 35 which my invention especially relates in the extreme position opposite to that which the same parts occupy in Fig. 1, and

Fig. 5 a diagrammatic view for illustrating the point of contact between levers B and 40 34 at points intermediate the extreme points as shown in Figs. 1 and 4, one contact being indicated by whole lines at point x, and another by dotted lines at point z, both, as well as the contacts at the extreme positions of 45 said levers, being on a line y—y, being a straight line drawn through the axis of the pivots of the respective levers.

In said drawings, the portions marked A represent the frame for supporting the various 50 parts of the mechanism, B a pivoted lever carrying the operating pawl 21, and C the magnets.

The frame A is preferably a skeleton frame of cast metal of suitable size and arrangement to support the various parts of 55 the mechanism. It has transversely extend-

ing studs 10 and 11 near diagonally opposite corners, to the outer ends of which a bar 12 is secured by screws 13 and 14. The main arbor 15 on which the clock hands, or 60 other indicating means (not shown,) are adapted to be mounted, is set in a suitable bearing in said frame at one end, and at the other end in said bearing in bar 12.

The train of clock gearing is in the main 65 similar to that in common use, and requires no special description. It embodies the operating ratchet wheel 16 mounted on a sleeve surrounding arbor 15 and secured to said arbor 15 by friction through a spring yoke 70 17 in the usual manner.

Lever B is mounted on a pivot 18 on one side of the frame and extends in a substantially horizontal direction near to the opposite side of the frame, being provided with 75 a contact flange 19 on its outer end, which is adapted to contact with a stop 20 secured on a part of the frame above. Said lever B carries a pawl 21 mounted on a pivot 22, which pawl is formed with a weighted end 80 23 extending from said pivot at an angle with the part adjacent to the operating ratchet wheel 16. The lower end of said pawl is adapted to engage with the teeth of said ratchet wheel to operate the same as the 85 lever is vibrated. A member 24 is attached by screw 25 to the outer end of lever B. This member rests on the outer ends of pivots 22 and 26 to retain pawl 21 and verge 27 on said pivots. Said verge 27 extends 90 across from the top to the lower side of the mechanism and at its lower end is formed with a slot 28 mounted over a pin 29, on a part of the frame, which serves as a guide. Said verge is provided with teeth 30 and 31 95 on its opposite ends, which are adapted to coöperate on opposite sides of the ratchet wheel 16.

An armature 33, consisting of a rectangular block is provided with a projecting 100 arm 34, and is mounted on a pole-piece 35 on the upper ends of magnet C. Said armature 33 is pivotally supported by its sharp front corner resting on the top of said pole-piece against pins or stops 36, which project upwardly from the top surface of said pole-piece from its rear edge. Said corner of armature is in line with, or exactly crosses, a point that would meet a continuation of the curve of contact edge of 110 arm 34. This is important, for if the curved line on top edge of arm 34 does not

terminate on the corner of the armature on which it pivots, there will be a slip or drag between the curved surfaces, producing a waste of power, as the contact between the 5 two would not be a perfect rolling contact. The arm 34 extends under the arm B and the adjacent edges are adapted to cooperate in the operation of the mechanism. The adjacent edge of the arms 34 and B have a 10 curvature of exactly the same form and length but are not an arc of a true circle. In the position shown in Fig. 1 the magnets are deenergized and the edge of arm B is shown as resting upon the edge of arm 34 15 close to its inner end, or close to the magnet. As soon as the magnets are energized by the closing of the circuit by a circuit closer in the master clock (not shown) the magnetic force draws armature 33 downward 20 to bring its lower edge parallel with the face of the pole-piece 35, which serves to bring arm 34 into the position shown in Fig. 4. It will thus be seen that at the beginning of the period of operation, while 25 the field through which the magnetic current must travel is widest and its magnetic pull the weakest, the leverage for lifting the arm B, pawl 21 and verge 27 carried by the arm B through the lever 34 is very 30 short, and while the armature is approaching the pole-piece and the strength of the magnetic pull is increasing, the operative part of lever 34 lengthens and the operative part of arm B shortens in exact proportion 35 so that the total amount of work required to operate the secondary clock is distributed in proportion to the increasing power of the magnet from its weakest to its strongest pull throughout its movement. In other 40 words, the distance between the fulcrum and the weight lengthens in proportion to the increase of power caused by the approach of the armature to the magnets. It will also be seen that the motion between 45 the contacting surfaces of the lever 34 and arm B is always and only a rolling motion and no dragging of one over the other with the resulting friction and waste of power is allowed. By this means the total power 50 exerted upon the armature is utilized to move the secondary clock, therefore requiring a very much less current, and causing the armature to approach the magnet at a uniform speed, obviating the jar and sharp 55 sound when the armature stops, which is so very characteristic in all devices operated by the direct pull of a magnet. The adjacent edges of the two arms B and 34 simply roll on each other throughout their entire 60 movements, the point of contact between them always being in a straight line between the centers of the pivot 18 and the point of rest at the corner of the armature 33. Thus it will be readily seen and understood 65 that the magnetic energy is fully uti-

lized, from the fact that my mechanism provides a graduated leverage, so that the leverage is always in proportion to the power, thereby eliminating the necessity of providing a magnet of a total energy very 70 much greater than is required to perform the actual work.

A pawl 37 is pivoted to the bar 12 and holds ratchet wheel 16 from return movement. 75

The operation will be readily understood from the foregoing description of the apparatus. When the magnet is energized armature 33 is attracted thereto and, as above described, serves to lift arm B carrying with it pawl 21 the distance of one tooth of ratchet wheel 16, or from a position of rest against the back of one tooth to a position of rest against the back of next tooth, also lifting verge 37 to withdraw tooth 30 from between teeth of said ratchet wheel on the top side and bring tooth 31 to between the teeth of said ratchet wheel on the lower side. The teeth 30 and 31 and verge 37 prevent all possibility of the clock racing. The deenergizing of the magnet causes said parts to fall and by their weight to relieve the ratchet wheel from engagement with tooth 31 and through pawl 21 cause said ratchet wheel to move one tooth and bring tooth 95 30 of the verge into engagement with the next tooth of said ratchet wheel. The turning of the ratchet wheel in this manner, step by step, operates in the train of gearing, as is well understood, to turn the 100 arbor 15 and the hands of the clock or other indicating means carried thereby.

Having thus fully described my said invention, what I claim as new and desire to secure by Letters Patent, is:

1. In a secondary electrically operated clock mechanism, the combination with the operating magnets, ratchet-wheel and pawl-carrying lever, of an armature having an operating lever rigid therewith and arranged with its upper edge in contact with the lower edge of said pawl-carrying lever, the edges of said two parts being equally curved but in reverse directions and of the same length along their contact faces, said armature being mounted to rock on a support adjacent the pole of the magnets, substantially as set forth. 105

2. An electrically operated clock mechanism comprising a ratchet-wheel, a clock 120 train, a weighted lever pivoted to one side of the frame carrying a pawl engaging with the teeth of the ratchet-wheel and with a verge extending across the ratchet-wheel and provided with pallets adapted to engage 125 alternately with opposite sides of said ratchet-wheel, a magnet, a tilting armature mounted adjacent the pole of said magnet and provided with a rigid arm extending across the clock frame with its upper edge 130

supporting the lower edge of said pivoted lever, the contacting edges of said arm and lever being formed curved and arranged to maintain the point of contact in line between the pivot of the lever and the pivot of said armature, substantially as set forth.

3. An electrically operated clock mechanism comprising a clock train, a magnet, an operating ratchet-wheel, a pivoted lever carrying the verge and operating pawl, an armature carrying an oscillating arm and mounted to rock on a support adjacent the pole of said magnet, the upper edge of said arm being arranged in contact with the lower edge of said lever and the contacting faces of said arm and lever being curved and formed to maintain the point of contact between said faces on a line between the pivot of the arm and the pivot of the armature, substantially as set forth.

4. An electrically operated clock mechanism comprising a clock train, a magnet, an operating ratchet-wheel, a pivoted lever carrying the means for advancing said ratchet-wheel step by step, a pivoted arm

connected to be operated by the magnet and arranged with a bearing face in contact with the bearing face of said lever, said bearing faces of said respective parts being formed on a curve to maintain the point of contact between said parts on a line between their respective pivots, substantially as set forth.

5. In a clock, the combination with an escapement wheel, of a lever forming a weighted arm and a verge arm, pallets carried by said verge arm to engage the escapement wheel, a driving pawl carried by said lever, electro-magnetic means for intermittently moving said lever in one direction and means for preventing retrograde movement of said escapement wheel.

In witness whereof, I have hereunto set my hand and seal at Waynesboro, Pennsylvania, this twenty-fourth day of May, A. D. 1915.
